UNITED STATES PATENT OFFICE.

ALVIN L. BUFFINGTON, OF MINNEAPOLIS, MINNESOTA.

DESIGN FOR A LAMP-BODY.

SPECIFICATION forming part of Design No. 31,856, dated November 21, 1899.

Application filed January 20, 1898. Serial No. 667,347. Term of patent 7 years.

To all whom it may concern:

Be it known that I, ALVIN L. BUFFINGTON, a citizen of the United States, residing in the city of Minneapolis, county of Hennepin, 5 State of Minnesota, have invented and produced a new and original Design for a Lamp-Body, of which the following is a specification, reference being had to the accompanying drawings, forming a part thereof.

10 Figure 1 is a right side elevation, Fig. 2 is a right side elevation with some parts broken away, and Fig. 3 is a front elevation, of a lamp-body embodying my design.

By reference to said drawings it will be 15 seen that the body or case of the lamp-body is of spheroidal form, being a sphere truncated at one point to form its face and being provided at this face with a concavity or spheroidal depression. Through the center 20 and on the axis of the concave face a gas-burner projects outward.

The general appearance of the lamp-body is that of a ball or sphere, and its face is pro-

vided with a skeleton-like mask or guard, which completes the spherical form of the 25 spheroidal body-section and incloses the concave face and its centrally-located and axially-projected gas-burner. When the lamp-body is viewed from its face or front, the gas-burner is seen projecting endwise toward 30 the observer.

Lamps of the above design were particularly designed for use as acetylene-gas lamps for bicycles; but they are, of course, well adapted for more general use. 35

Having described my invention, what I claim as new, and desire to secure by Letters Patent of the United States, is—

The design for a lamp-body substantially as herein shown, and described. 40

Dated at Minneapolis, Minnesota, this 15th day of January, 1898.

ALVIN L. BUFFINGTON.

In presence of—

LILLIAN C. ELMORE,
FRANK D. MERCHANT.
